UNITED STATES PATENT OFFICE.

LUELLA CORNELL, OF BROOKLYN, NEW YORK.

OPERATING APPLIANCE FOR ANGLE-COCKS FOR AIR-HOSE.

1,393,882.

Specification of Letters Patent. Patented Oct. 18, 1921.

Application filed July 2, 1920. Serial No. 393,611.

To all whom it may concern:

Be it known that I, LUELLA CORNELL, a citizen of the United States, and a resident of Brooklyn, county of Kings, and 5 State of New York, have invented certain new and useful Improvements in Operating Appliances for Angle-Cocks for Air-Hose; and I do hereby declare the following to be 10 a full, clear, and exact description of one form of my invention, reference being had to the accompanying drawing, forming a part of this specification.

This invention relates to mechanism for operating the valve in the air brake hose on 15 the end of cars of various kinds, which is generally termed an angle cock; and which device has its plug or valve turned by a lever that is pivoted thereon, and is normally held against a stop that would prevent turn- 20 ing of the valve by the lever, but when the lever is swung up the plug can be turned by the lever.

The object of the present invention is to 25 provide means for turning the angle cock from the top or upper part of the car.

A further object of the invention is to provide such operating means that will first swing the lever on the cock, and then turn the lever to open or close the valve.

30 In the accompanying drawing showing one embodiment of my invention, Figure 1 shows the end portion of a car with the angle cock, and the operating means.

Fig. 2 is a partial sectional view looking 35 downward, taken above the slotted guide.

Fig. 3 is a similar view with the valve shifted.

Fig. 4 shows the upper guide for the operating rod.

40 Fig. 5 shows the slotted guide.

Fig. 6 shows the angle cock.

As set forth in the drawing, the car has the end denoted by 1, and the usual form of angle cock 2 is shown on the end sill of 45 the car. This angle cock has a plug or key 3, with a lever 4 pivoted to the plug at 5, to turn the plug and open or close the valve. This lever is provided with an eye 6 for engagement with an operating member, extending to the top of the car. A stop 15 on the lever engages a lug 16 on the angle cock and prevents turning of the plug 3, until the lever is swung upward.

I provide means for swinging this lever 55 to release it from the lug, and for also causing the lever to turn the plug of the cock,

which means are operable from the top of the car. I show an operating rod 7 having a handle 8 at its upper end, adjacent the top of the car. This operating rod is shown supported in an eye bolt 9, secured to the car end, and a collar 10 is shown clamped on the rod to limit the downward movement. The lower end of the rod 7 has a suitable connection with the lever 4, preferably by having a spring hook 11 whereby it can detachably engage the eye 6 of the lever.

It will be readily understood that a trainman on top of the car can grasp the handle 8 of the operating rod, and by drawing upward on this rod will swing the lever 4 upwardly, to release it from the locking lugs. Thereupon the handle 8 and rod are given a twist, which will cause the lever to swing to one side, and turn the plug of the angle 75 cock.

I also provide a special guide member for the operating rod that will cause the rod at the lower portion to move rearward at a slight angle, of about thirty degrees to the 80 side of the car, which is the angle at which the lever of the angle cock is normally positioned. The rod 7 will at its lower portion move back at this angle, and then as the lever and cock is swung it will move toward the 85 side of the car, at a right angle to its former direction of movement. I provide a special guide, shown in the form of a threaded stem 12 having slotted arms 13 and 14, see Fig. 5. This guide is bolted to the car end 1, with 90 the operating rod 7 extending through the slotted arm. The arm 13 extends forward at an angle of about one hundred and twenty degrees to the stem 12, and the slotted arm 14 extends toward the side of the car at a 95 right angle to the other arm, with the slots connecting as shown. This guide is attached to the car with the rod 7 in its normal position located at the outer end of the slotted arm 13.

In the operation of this device, the rod 7 is first raised by the handle which will swing the lever 4 upwardly and release it from the lug 16, and the rod 7 will move back in the slot 13, when the rod 7 can be turned to swing the plug and the rod will then move through the slot 14 of the guide. When released the rod 7 will move downward and the lever 4 will swing downward. To turn the plug to the reverse position the same 105 operation is performed, the rod 7 is first raised, then turned to swing the lever 4 and

then released which will return the several parts to their former position.

It is to be understood that various changes can be made by those skilled in this art, with 5 in the purview of the claims, without departing from the spirit and scope of my invention.

What I claim is:—

1. The combination with a car provided 10 with an air hose having an angle cock with a hinged plug lever of an upright operating rod movably mounted on the car end, said rod having a movable connection with said lever, said rod being supported on the car 15 to turn and also to be raised, whereby the operating rod can be moved upward to raise the said lever and thereupon turned axially to cause said lever to cause said lever to swing the angle cock plug.
- 20 2. The combination with a car provided with an air hose having an angle cock with a hinged plug lever, of an upright operating rod movably mounted on the car end, said rod having a movable connection with said 25 lever and extending to the car top, said rod being supported on the car to turn and also to be raised, whereby the operating rod can be moved upward to raise the said lever and thereupon turned axially to cause said lever 30 to swing the angle cock plug, and a slotted

guide on the car end engaging the operating rod plug.

3. The combination with a car provided with an air hose having an angle cock with a hinged plug lever, of an upright operating 35 rod movably supported on the car end, said rod having a movable connection with said lever and extending to the car top, said rod being supported on the car to turn and also to be raised, whereby the operating rod can 40 be moved upward to raise the said lever and thereupon turned axially to cause said lever to swing the angle cock plug, and a guide on the car end having an angular slot en- 45 gaging the operating rod to guide the rod to shift in two directions, whereby the said rod will first move rearward in the slot to raise the lever, and thereupon move laterally in the slot on turning of the angle cock plug.

4. The combination with a car provided 50 with an air hose and an angle cock at the car end connection, of an upright operating rod movably supported on the car end and ex- 55 tending to the car top, said rod being connected with the angle cock plug whereby the operating rod can be swung into position to turn the angle cock plug.

Signed at New York city, N. Y., on June 30th, 1920.

LUELLA CORNELL.
